US00D843808S

(12) **United States Design Patent** (10) **Patent No.:** **US D843,808 S**
Bloch (45) **Date of Patent:** **** Mar. 26, 2019**

(54) **KNIFE**

(71) Applicant: **Outdoor Edge Cutlery Corporation**,
Denver, CO (US)

(72) Inventor: **David R. Bloch**, Morrison, CO (US)

(73) Assignee: **OUTDOOR EDGE CUTLERY
CORPORATION**, Denver, CO (US)

(**) Term: **15 Years**

(21) Appl. No.: **29/614,719**

(22) Filed: **Aug. 22, 2017**

Related U.S. Application Data

(63) Continuation of application No. 29/551,898, filed on Jan. 18, 2016, now Pat. No. Des. 795,040, which is a continuation of application No. 29/507,929, filed on Oct. 31, 2014, now Pat. No. Des. 747,637.

CLAIM

The ornamental design for a knife, as shown and described.

DESCRIPTION

FIG. 1 is a perspective view of the knife;
FIG. 2 is a front elevation view thereof;
FIG. 3 is a rear elevation view thereof;
FIG. 4 is a right elevation view thereof;
FIG. 5 is a left elevation view thereof;
FIG. 6 is a top plan view thereof;
FIG. 7 is a bottom plan view thereof;
FIG. 8 is a perspective view of another embodiment of the knife;
FIG. 9 is a front elevation view thereof;
FIG. 10 is a rear elevation view thereof;
FIG. 11 is a right elevation view thereof;
FIG. 12 is a left elevation view thereof;
FIG. 13 is a top plan view thereof; and,
FIG. 14 is a bottom plan view thereof.
The broken lines depict portions of the knife in which the design is embodied that are not considered part of the claimed design.

1 Claim, 8 Drawing Sheets
